DESIGN FOR A CEREAL BOWL OR SIMILAR ARTICLE

George L. Jenks, Chicago, Ill.

Application October 30, 1935, Serial No. 59,271

Term of patent 7 years

To all whom it may concern:

Be it known, that I, George L. Jenks, a citizen of the United States, residing at Chicago, in the county of Cook and State of Illinois, have invented a new, original, and ornamental Design for a Cereal Bowl or Similar Article, of which the following is a specification, reference being had to the accompanying drawings, forming part thereof.

Figure 1 is a top plan view of a cereal bowl showing my new design.

Fig. 2 is a side elevational view of the same.

Fig. 3 is an underside elevational view.

Fig. 4 is a fragmentary sectional view taken approximately in the plane of line 4—4 of Figure 1 but on an enlarged scale.

The dominant feature of the design resides in the opaque base applied to the bottom of a transparent bowl body and having a narrow upwardly facing peripheral edge portion underlying and clearly visible through the transparent bottom, substantially as shown.

I claim:

The ornamental design for a cereal bowl or similar article, substantially as shown and described.

GEORGE L. JENKS.
